**BOOK DISCHARGING MECHANISM IN
CASING-IN MACHINE**

James H. Thorp, West Hartford, Conn., assignor to The Smyth Manufacturing Company, Bloomfield, Conn., a corporation of Connecticut

Filed Aug. 11, 1966, Ser. No. 571,847
10 Claims. (Cl. 198—133)

ABSTRACT OF THE DISCLOSURE

A book discharging mechanism comprising a split horizontal plate which engages books moved downwardly on saddle plates and arrests book movement, and a book transfer device which engages an arrested book and urges the same horizontally out of the path of saddle plate movement.

The present invention relates to a high speed casing-in machine and, more particularly, to a book discharging mechanism particularly adapted for use in such a machine.

It is the general object of the present invention to provide a book casing-in machine wherein books are carried astride saddle plates movable downwardly in a vertical path and wherein there is provided a book discharging mechanism operable to remove books in succession and in a high speed operation and yet in a gentle manner for delivery to a discharge conveyor or the like.

A further and more specific object of the invention resides in the provision of a book discharging mechanism of the type mentioned wherein the books are removed in succession from downwardly moving saddle plates in an endwise horizontal movement as the saddle plates are withdrawn downwardly from the books, a high degree of speed and efficiency in book removal thus being achieved.

The drawings show a preferred embodiment of the invention and such embodiment will be described, but it will be understood that various changes may be made from the construction disclosed, and that the drawings and description are not to be construed as defining or limiting the scope of the invention, the claims forming a part of this specification being relied upon for that purpose.

Of the drawings:

FIG. 1 is a somewhat schematic front elevation of a casing-in machine including a book discharge mechanism embodying the present invention;

FIG. 2 is an enlarged perspective view showing the book discharge mechanism in greater detail;

FIG. 3 is an enlarged perspective view similar to FIG. 2, but showing the book discharge mechanism from an opposite corner perspective angle;

FIG. 4 is a vertical sectional view taken generally as indicated at 4—4 in FIG. 2;

FIG. 5 is a fragmentary top view taken of a portion of the book discharge mechanism comprising particularly a book transfer device;

FIG. 6 is a vertical section taken generally as indicated at 6—6 in FIG. 2 and showing a book in an upright position adjacent a book tilting device; and

FIG. 7 is a vertical sectional view taken generally as indicated at 7—7 in FIG. 2, but showing a book in a partially tilted position under the urging of the book tilting device.

Referring particularly to FIG. 1, it will be observed that a book casing-in machine 10 is shown with a plurality of saddle plates 12, 12. Each of the saddle plates 12, 12 is adapted to support a book or a book filler in a back-up attitude and astride an upper portion of the plate. Thus, a book can be split or spread apart slightly approximately at its center leaves so as to rest astride the saddle plate 12. The saddle plates 12, 12 are moved by means of a

2

conveyor chain 14 in a generally vertical path through an upward run or pass at the left and through a downward run or pass at the right. As is explained fully in my co-pending application entitled, Book Casing-In Machine, Ser. No. 571,571, filed Aug. 10, 1966, book components comprising fillers and cases are assembled at the left-hand portion of the machine and each saddle plate 12, moving upwardly at the top of the left-hand pass or run, carries a completed book such as the books 16 shown. At the right-hand portion of the machine, it is necessary to remove the books 16, 16 from the saddle plates 12, 12 in the vertically downward run or pass of the conveyor belt 14. Removal of the books from the plates occurs at a Book Discharge Station A and by means of a book discharge mechanism indicated generally at 18.

Considering the conveyor chain 14 in greater detail, it will be observed that the said chain is mounted on and engaged with four rectangularly spaced sprockets 20, 20. The sprockets or sprocket wheels 20, 20 drive the chain in a clockwise direction and, more particularly, the upper left-hand sprocket wheel 20 may be regarded as a drive sprocket while the remaining sprocket wheels 20, 20 may be considered mere idlers. Each saddle plate 12, 12 is pivotally secured to the conveyor chain 14 so as to depend continuously therefrom in a substantially vertical plane. Thus, books such as the books 16, 16 shown on the plates 12, 12 move downwardly in succession at the right-hand portion of the machine for removal from the machine by the book discharge mechanism.

The book discharging mechanism 18 comprises a book abutment and support means which is adapted to accommodate the downward passage of a saddle plate and to engage and arrest the downward movement of a book on the saddle plate for the downward withdrawal of the plate from the book. Said abutment and support means is shown as comprising an abutment member or bar 22 which is split longitudinally for the downward passage of a saddle plate and which is of such width as to engage the lower surface of a filler portion of a book and yet allow the lower edges of the case of such book to be received adjacent and to clear the opposite sides thereof, FIG. 4. Thus, the engagement of the book with the abutment member or bar does not tend to dislodge the case from the filler but instead tends to maintain firm engagement therebetween. As best shown in FIG. 2, a guide means is provided above the abutment member for engaging and urging firmly closed opposing portions of a case of a book and such means comprises guide plates 24, 24. Further, guide plates 26, 26 best shown in FIG. 4, are adjustable toward and away from the abutment member or bar 22 by means of suitable racks 28, 28 and pinions 30, 30. Pinions 30, 30 may be turned by suitable hand knobs 32, 32, one shown, FIG. 2.

The abutment or stop member or bar 22 may be set to have one portion wherein the books on the saddle plates engage the said member or bar and it also has another portion which extends away from the aforesaid vertical path of saddle plate movement and along which books may be urged for discharge from the machine. A book transfer means for urging the books along the abutment bar in horizontal and endwise fashion preferably comprises a pair of pusher fingers 34, 34 and operating means therefore. The pusher fingers 34, 34 are arranged for horizontal reciprocal movement whereby they can be engaged with a rear portion of a book at said one portion of the abutment bar 22 and moved horizontally to urge the book along the bar to its said other portion for discharge from the machine. Each finger 34 has an associated finger carriage 36 which is reciprocally moved in a horizontal direction in the machine and each said finger is slidably held in its carriage for movement of the finger into and out of the

horizontal path of book movement between said one and other positions on said abutment member 22. Thus, the fingers 34, 34 are slidable in the carriages 36, 36 and they are urged inwardly into the path of book movement by means of suitable springs 38, 38. A cam means is provided for maintaining each pusher finger out of the path of book movement as the carriages 38, 38 are moved rightwardly in FIG. 5 or during return strokes of the fingers.

As is best illustrated in FIGURES 4 and 5 each finger 34 has an associated cam roller 40 which is movable and a cam track 42. That is, each roller 40 is movable in an inner portion 42a of the cam track 42 during a forward or book moving stroke of its associated pusher finger 34. A front gate 44 is engaged by the roller 40 at a forward end of the book transporting stroke of the finger such that the roller 40, at an initial portion of a return stroke, engages the gate and moves outwardly to a portion 42b of the cam track. As the finger continues to move rearwardly, or on a return stroke, the roller 44 is thus urged outwardly and the finger is urged outwardly so as to be removed from the horizontal path of book movement. At a rear end portion of a rearward stroke of a pusher finger 34 its associated roller 40 engages a cam surface 46 which is inclined to urge the roller inwardly and to thus urge the pusher finger inwardly to the broken line position shown in FIG. 5. As will be apparent, the pusher finger 34, in its broken line position, is disposed in readiness for a forward or book transporting stroke.

Operating means for the carriages 36, 36 and the pusher fingers 34, 34 are identical and are best illustrated in FIGS. 2 and 4. Each carriage 36 is slidable along a longitudinal bar 48 and has a slide 50 formed at a lower portion thereof. The slide 50 extends vertically and has disposed therein a carriage drive member 52 which is mounted upon a sprocket chain 54. The carriage drive member 52 is movable with the sprocket drive chains 54 whereby to slide its associated carriage 36 forwardly and rearwardly in a reciprocal movement along the support bar 48.

Sprockets 56, 56 carry the sprocket chain 54 and a forward sprocket 56 has connected therewith a stub shaft 58 which extends outwardly to a gear 60. The gear 60 is thus connected in driving relationship with the forward sprocket 56 and is in turn driven by a larger gear 62 mounted upon a connecting shaft 64. The gears 62, 62 on the connecting shaft 64 are driven by a small double gear 66 in turn drivingly connected with a double gear 68 on a shaft 70. The shaft 70 extends rearwardly in the machine to a sprocket 72 which is driven by a sprocket chain 74 in turn driven by a sprocket 76 and the main drive chain or conveyor chain 78 thus shown in FIG. 2.

From the foregoing it would be apparent that the pusher fingers 34, 34 can be operated to move books in succession from the said one or rear portion of the abutment member 22 forwardly to said other or front portion thereof. As each book is moved downwardly on its saddle plate and engages the abutment member, the pusher fingers are moved inwardly therebehind and urges the same forwardly along the abutment bar in timed relationship with the downward movement of the saddle plate. Preferably and in the book discharging mechanism shown, the timing of the saddle plate movement and the movement of the pusher fingers 34, 34 is such that the books are moved forwardly in endwise fashion from a saddle plate as the saddle plate is withdrawn downwardly from the book. Thus, high speed operation can be achieved and yet books can be handled in a gentle manner by the discharge mechanism.

The said other or forward portion of the abutment bar 22 has associated therewith a book tilting device indicated generally at 80 and a discharge conveyor 82. The discharge conveyor 82 is partially shown and comprises a belt 84 and a roller 86 over which the belt extends. The belt is inclined downwardly and is adapted to remove books from the book discharging mechanism generally

5 at right angles with respect to their movement from the said rear or one portion of the abutment bar 22 to the said other or forward portion thereof. As will be apparent, a book falling upon the discharge conveyor belt 84 will be transported away from the book discharging mechanism and it is only necessary to tilt the book from its upright position in order to cause it to fall upon such conveyor belt.

10 The book tilting device 80 comprises a tilting plate 88 which is supported pivotally by means of a pivot shaft 90 and brackets 92, 92. The brackets 92, 92 carry small racks 94, 94 which support the tilt plate 88 and which are movable for adjustment of the plates at the urging of small pinions 96, 96. The pinions 96, 96 are mounted upon a shaft 98 which is in turn rotatable at the urging of a hand knob 100. The pivot shaft 90 is rotated by means of an arm 102 connected therewith at a central portion and extending to a short push rod 104. The push rod 104 extends downwardly to one end portion of 106 of a lever 108 pivoted above a stub shaft 110. A second arm portion 112 of the lever 108 carries a cam follower 114 engageable with a cam 116. The cam 116 is driven by the aforementioned bevel gear 68 whereby to oscillate the lever 108, to vertically reciprocate the push rod 104, to oscillate the lever 25 102 and thereby to oscillate the pivot shaft 90 and the tilt plate 88 as required to tilt books onto the conveyor 84.

30 Preferably a book holding member is operatively associated with the tilt plate 88 and such a member is shown at 120 in FIGS. 6 and 7. The said member is slidable vertically to an upper position shown in FIG. 6 where it holds a book upon the abutment bar 22 and to a lower position as shown in FIG. 7 where it allows the book to be urged by the tilt plate 88 onto the conveyor 84. Adjustment of the book holding member 120 to accommodate 35 books of different thicknesses provided for by means of a hand knob 122 and a small worm 124. A rack 126 is connected with the holding member and has an associated pinion 128 which is rotated by a small arm 130. The arm 130 is swung in an arc by means of a push rod 132 connected with the aforementioned arm 102 and, more specifically, with a pivot pin 134 associated with said arm. As will be apparent, swinging movement of the arm 102 as aforesaid will result in movement of the push rod 132 swinging the short arm 130 so as to oscillate the pinion 128. Oscillation of the pinion 128 will serve to urge the rack 126 upwardly and downwardly as required to urge the book holding member 120 to its upper and lower positions as aforesaid. Timing of the mechanism is such that the holding member is moved to its lower position and 50 as the tilt plate 88 is moved to the tilt position as shown in FIG. 7. Similarly the holding member is moved to its upper position as the tilt plate 88 is moved to its rear or none working position shown in FIG. 6.

55 The invention claimed is:

1. The combination in a book casing-in machine comprising at least one saddle plate arranged in a substantially vertical plane and adapted to support a book thereon in a back-up attitude and astride an upper portion of the plate, a conveyor means for continuously moving the 60 saddle plate downwardly in a generally vertical path, a book discharge station disposed in the path of saddle plate movement and comprising a stationary apertured book abutment and support means adapted to accommodate the downward passage of a saddle plate therpast and to engage and arrest the downward movement of a book thereon for downward withdrawal of the plate from the book, and book transfer means movable relative to said abutment and support means at said discharge station and engageable with a book engaged and supported by said abutment means and to urge the book generally horizontally and in endwise fashion out of said vertical path of saddle plate movement.
- 65 2. The combination in a book casing-in machine as set forth in claim 1 wherein said conveyor means and book transfer means are interconnected for operation in timed

relationship such that a book is moved in endwise fashion from a saddle plate during downward withdrawal of the plate from the book.

3. The combination in a book casing-in machine as set forth in claim 1 wherein said book abutment and support means comprises a horizontally elongated upwardly exposed abutment member having one portion thereof disposed in said vertical path of saddle plate movement and split for the downward passage of a saddle plate therethrough, and having another portion thereof arranged to extend away from the aforesaid vertical path of saddle plate movement, and wherein said book transfer means is arranged to engage a book on said one portion of said member and to slide the book along said member to said other portion thereof.

4. The combination in a book casing-in machine as set forth in claim 3 wherein said elongated member is of such width as to engage the lower surface of a filler portion of a book conveyed downwardly into engagement therewith by a saddle plate, the lower edges of the case of such a book being received adjacent and clearing the opposite sides of said member.

5. The combination in a book casing-in machine as set forth in claim 4 wherein said book transfer means comprises a pair of pusher fingers and operating means for effecting horizontal reciprocal finger movement whereby the fingers are engaged with a rear portion of a book on said one portion of said abutment member and thereafter operable to slide the book to said other portion of the member.

6. The combination in a book casing-in machine as set forth in claim 5 wherein each said pusher finger is slidably supported for movement into and out of the horizontal path of book movement between said one and other portions of said abutment member, wherein biasing means is provided for urging each finger into the path of book movement, and wherein cam means is provided for maintaining each finger out of the path of book movement during return movements of the finger from said other to said one portion of the abutment member, said cam means being inoperative and the biasing means

being operative during book transporting movements of the finger to urge the finger into said path of movement behind a book.

7. The combination in a book casing-in machine as set forth in claim 6 wherein each said pusher finger is operatively connected with and driven by a sprocket wheel and chain device for reciprocal movement adjacent and parallel with the aforesaid horizontal path of book movement.

10 8. The combination in a book casing-in machine as set forth in claim 5 wherein a guide means is provided above said abutment member for engaging and urging firmly closed opposing portions of the case of a book moving downwardly on a saddle plate toward said abutment member.

15 9. The combination in a book casing-in machine as set forth in claim 5 wherein a discharge conveyor is provided laterally adjacent said other portion of said abutment member, and wherein a book tilting device is provided adjacent said member on a side thereof opposite the discharge conveyor, said device being operable to engage a book in an upright back-up attitude on said member and to tilt the book toward its side and thereby cause the same to fall onto said discharge conveyor.

20 10. The combination in a book casing-in machine as set forth in claim 9 wherein there is provided on a side of said abutment member opposite said tilting device a book holding element, said element being movable to an operative position where it holds a book on said abutment member and to an inoperative position where a book is allowed to fall onto the conveyor at the urging of the book tilting device, and wherein there is provided a means for operating said book tilting and book holding devices in timed relationship with each other.
